US00D580048S

(12) **United States Design Patent**
Guney et al.

(10) **Patent No.:** **US D580,048 S**
(45) **Date of Patent:** **** Nov. 4, 2008**

(54) **SWIVEL ELBOW FOR MASK ASSEMBLY**

(75) Inventors: **Memduh Guney**, Killara (AU);
Anthony Michael Ging, Vancouver (CA); **Perry David Lithgow**, Glenwood (AU); **Jim Saada**, Kellyville (AU);
Amal Shirley Amarasinghe, West Pennant Hills (AU); **Joanne Elizabeth Drew**, Balgowlah Heights (AU);
Borivoje Ljubojevic, Ryde (AU);
Timothy Tsun-Fai Fu, Carlingford (AU)

(73) Assignee: **ResMed Limited**, Bella Vista (AU)

(**) Term: **14 Years**

(21) Appl. No.: **29/287,918**

(22) Filed: **Oct. 2, 2007**

Related U.S. Application Data

(60) Continuation of application No. 29/232,936, filed on Jun. 27, 2005, now Pat. No. Des. 556,897, which is a continuation of application No. 29/209,720, filed on Jul. 21, 2004, now Pat. No. Des. 540,464, which is a division of application No. 29/170,561, filed on Nov. 8, 2002, now Pat. No. Des. 496,098.

(57) **CLAIM**

The ornamental appearance for a swivel elbow for mask assembly, as shown and described.

DESCRIPTION

FIG. 1 is a front view of a swivel elbow for mask assembly according to a first embodiment of my/our design;

FIG. 2 is a rear view thereof;

FIG. 3 is a right side view thereof, with the left side view being a mirror image;

FIG. 4 is a top view thereof;

FIG. 5 is a bottom view thereof;

FIG. 6 is a front perspective view thereof;

FIG. 7 is a front view of a swivel elbow for mask assembly according to a second embodiment of my/our design;

FIG. 8 is a right side view thereof, with the left side view being a mirror image;

FIG. 9 is a top view thereof; and,

FIG. 10 is a bottom view thereof.

Where included, broken lines showing environment or structure are for illustrative purposes only and form no part of the claimed design.

1 Claim, 8 Drawing Sheets
